(57) **CLAIM**

The ornamental design for a discharge device, as shown and described.

DESCRIPTION

FIG. 1 is a front perspective view of a first embodiment of a discharge device showing our new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a cross-sectional view taken along the line 8-8 in FIG. 6;

FIG. 9 is a front perspective view of a second embodiment of a discharge device showing our new design;

FIG. 10 is a front view thereof;

FIG. 11 is a rear view thereof;

FIG. 12 is a first side view thereof;

FIG. 13 is a second side view thereof;

FIG. 14 is a top view thereof;

FIG. 15 is a bottom view thereof;

FIG. 16 is a cross-sectional view taken along the line 16-16 in FIG. 14;

FIG. 17 is a front perspective view of a third embodiment of a discharge device showing our new design;

FIG. 18 is a front view thereof;

FIG. 19 is a rear view thereof;

FIG. 20 is a first side view thereof;

FIG. 21 is a second side view thereof;

FIG. 22 is a top view thereof;

(Continued)

FIG. 23 is a bottom view thereof; and, FIG. 24 is a cross-sectional view taken along the line 24-24 in FIG. 22.

The even broken lines in the drawings represent portions of the discharge device that form no part of the claimed design. Additionally, the dash-dot-dashed lines in the drawings define the boundaries of the claimed design.

1 Claim, 24 Drawing Sheets
